JALOUSIE JAMB

Aaron L. Jaffa, 12 Salem Drive, North Providence, R.I.

Filed Feb. 1, 1960, Ser. No. 59,215

Term of patent 3½ years

(Cl. D13—6)

FIG. 1

FIG. 1 is a rear perspective view of a jalousie jamb showing my new design with a portion broken away to indicate indeterminate length;

FIG. 2 is an end view thereof; and

FIG. 3 is a perspective view as in FIG. 1, but from the front.

I claim:

The ornamental design for a jalousie jamb, substantially as shown.
